GEORGE WILLIAM HAWKSLEY AND MATTHEW WILD, OF SHEFFIELD,
ENGLAND.

Letters Patent No. 78,370, dated May 26, 1868.

IMPROVED COMBINATION OF A PUDDLING-FURNACE WITH A STEAM-GENERATOR.

The Schedule referred to in these Letters Patent and making part of the same.

TO WHOM IT MAY CONCERN:

Be it known that we, GEORGE WILLIAM HAWKSLEY and MATTHEW WILD, of Sheffield, England, have invented an Improved Combination of Furnace and Steam-Generator; and the following is a full description of the same.

Our invention consists in an arrangement and construction of furnace to be applied to the tubes or internal parts of boilers now used for generating steam or other water-jackets.

This novel arrangement is to be employed for various purposes, such as "puddling" and boiling metals, or for boiling or heating other materials or substances, the flue or internal arrangement of the boiler or the "water-jacket" being constructed and adapted to the various dimensions necessary to receive such furnaces, which are so arranged that the various operations for which they may be required can be effected conveniently from the outside. For example, to adapt a furnace for the purpose of puddling and simultaneously generating steam in the boiler, the furnace would be so constructed that the portion or space behind the "bridge" may be rendered available for such purpose, for which object two openings would be made in the side of the boiler, instead of one opening at the end, as usual. One of these openings would be made in front of the bridge, and communicates with the furnace for supplying fuel thereto, and the other would be made at a point behind the bridge of the furnace, and communicates with the space or chamber containing the metal to be puddled, and through which opening the said operation would be carried on, through which any other required operation may be conducted, both openings being closed by doors, if necessary.

The nature and chief feature of the invention being the peculiar adaptation and combination of furnaces with boilers, so that the heat from such furnaces may be simultaneously available for boiling or heating metals, (or for boiling or heating other materials,) and for generating steam in the boiler containing the furnace, for which purposes the furnace and boiler are peculiarly constructed, as before described.

Secondly, our invention consists in an arrangement of tubes placed under the bottom or side plates (or both) of the puddling-chamber of the furnace, through which water circulates, such arrangement being employed and designed to regulate the temperature of the said plates, the water being supplied to the pipes from any cold-water tank, and is caused to pass through the tubes by pressure in any ordinary manner.

In order that the invention may be better understood and explained in detail, we have hereunto attached a sheet of drawings, made upon a scale of about one-half inch to the foot.

Figure 1 represents a longitudinal sectional elevation of a steam-boiler or generator. To the flue, or internal portion thereof, the puddling or metal-boiling furnace is shown applied. This view illustrates more particularly the peculiar arrangement and adaptation of a puddling-furnace to the internal portion of the boiler.

Figure 2 represents a transverse section of the same through the line A B.

Figure 3 represents an example of the same principle of combining boiler and furnace together. In these arrangements the boiler is supplied with two furnaces, but one only may be used if required.

Figure 4 being a transverse section of the same, taken below the bridge, through the line C D.

We would here remark that these figures and views are only shown as examples, as the combination of a puddling-furnace with a steam-boiler may be arranged in various ways, the arrangement here shown being also adapted for the purpose of heating long bars of metal.

In the various figures, *a a* is the outer shell of the boiler, and *b b* the main furnace, which is constructed and adapted for the purpose of puddling, boiling, or heating metal, and simultaneously generating steam. The fuel is fed into the furnace below the bridge through the door *c* in the front of the boiler, and the opening *d* communicates with the space or chamber *e*, containing the metal to be puddled or heated, through which opening or tube the ingots are passed, and the operation of puddling is to be carried on, or through which any other similar operation may be effected. The gases or products of combustion escaping from the puddling-furnace pass through the flue *g*, which may either be constructed as shown in fig. 1, or such flues may be elongated, and having a diminishing diameter, and extending beyond the furnace.

The bottom and sides or bottom of the furnaces or puddling-chambers may be supplied with series of serpentine pipes, through which cold water is caused to circulate by pumps or otherwise, for the purpose of regulating the temperature of the plates composing the sides or bottom of the furnace, as before described.

This arrangement of furnace, as shown near the line C D, is constructed more particularly for the purpose of heating bars or lengths of metal which are passed into the chamber or receptacle through the opening h, at the back of the boiler, the furnace i being only a slow-fire furnace to maintain the heat at the end of the chamber.

Having now described the said invention, we wish it to be understood that we claim—

The furnace e and boiler a, constructed as described, the former being located within the latter, in such manner as to be wholly surrounded by water, the arrangement being such that the heat of the furnace generates the steam of the boiler, as shown and described.

In testimony whereof, we have signed our names to this specification in the presence of two subscribing witnesses.

G. W. HAWKSLEY,
MATTHEW WILD.
